DOLL

Marie Wittmann, New York, N. Y.

Application November 27, 1934, Serial No. 754,955

7 Claims. (Cl. 46—173)

This invention relates to improvements in dolls and has particular reference to a head mounting therefor, the present application being a continuation in part of my co-pending application, Serial 5 Number 658,473, filed February 25, 1933.

An object of the invention is to mount the head of the doll for limited turning movement relative to the body thereof and to connect said elements in such manner that the head will be securely held 10 in position on the body.

Another object is to facilitate the mounting of the head upon the body by the provision of a connection between said elements which is of simple and practical construction and which enables the 15 head to be quickly disposed in position without the necessity of employing tools for this purpose.

The above and other objects will appear more clearly from the following detailed description when taken in connection with the accompanying 20 drawing which illustrates preferred embodiments of the inventive idea.

In the drawing:

Figure 1 is a vertical longitudinal section through the head and part of the body of a doll 25 constructed in accordance with the invention.

Figure 2 is a detailed elevation of the connecting member shown in Figure 1 which joins the head with the body of the doll.

Figure 3 is a view similar to Figure 1 illustrating a different form of connecting member.

Figure 4 is a sectional view taken at right angles to Figure 3.

Figure 5 is a view similar to Figure 3 showing still another form of connecting member, and

Figure 6 is a top plan view of the neck-piece forming a part of the doll body, the connecting member between said neck-piece and the head of the doll being shown in section.

Referring particularly to Figure 1, 10 indicates 40 the body of the doll which may be of rubber or any other suitable material, and 11 designates a neck-piece which may also be of rubber and which is disposed within the neck portion of the body 10 to effectively close and support said portion. The 45 head 12 of the doll may also be of any suitable material and is provided with an opening 13 in its bottom which is adapted to receive the upper end of the neck portion of the body 10 and snugly engage the same, the head having a limited turning movement upon said body as will presently appear.

The neck-piece 11 is provided with a pair of 50 depending aprons 14 designed to engage the chest and upper back portions of the doll to aid in supporting the same to prevent undue collapsing

thereof when the body 10 is made of rubber. The outer surface of the upper portion of the neck-piece 11 is provided with spaced circumferential beads 15 over the lower one of which is fitted the upper end of the neck portion of the body, and the upper of said beads overhanging the upper extremity of said body, said beads aiding in securing the neck-piece against shifting movement relative to the body and also rendering the latter water-tight at the neck portion thereof when the 10 body is utilized to form a water compartment as described in the above-mentioned co-pending application. In the upper central portion of the neck-piece 11 the same is provided with a recess 16 from the bottom of which extends a partition 15 or abutment 17, and the inner end of said recess is enlarged to provide channels or grooves 18 which extend about the walls of the recess to the abutment 17.

Means are provided for mounting and maintaining the head 12 upon the body 10 for limited turning movement thereon and for further assisting in the retention of the neck-piece 11 in proper relation to the adjacent portion of said body. Said means, as shown in Figures 1 and 2, comprises a 20 connecting member in the form of a yoke 19 suspended from an attaching member 20 in the form of a rod extending transversely of the head and having its ends imbedded in the sides of the latter. Extending downwardly from an intermediate point of the yoke 19 is a pair of diverging resilient arms 21 each of which has its free end 22 bent outwardly so as to engage in one of the grooves 18 in the neck-piece. When mounting the head 12 upon the body, the resilient arms 21 25 are pressed together and inserted into the recess 16 in the neck-piece in opposite sides of the abutment 17 until the ends 22 of said arms engage the bottom of said recess. The arms are then 30 released to permit the same to spread apart, whereupon said ends 22 will engage in their respective grooves 18. By engaging in said grooves, the ends 22 will contact a wall thereof and thereby 35 prevent withdrawal of the head from the body and any tendency of said head to be displaced by reason of an outward pull thereon will tend to wedge the tapered neck-piece 11 more securely in the neck portion of the body. The length of the connecting member is such that when the 40 same is in the position shown in Figure 1 it will at all times maintain a snug fit between the head 45 12 and the upper end of the body 10. At the same time, there is permitted a turning movement of the head upon the neck portion of the body which 50

55

will be limited by contact of the arms 21 with opposite sides of the abutment 17.

In the form of the invention illustrated in Figures 3 and 4, the body, head and neck-piece 5 may be of the same construction as shown in Figure 1 with the exception that the abutment 23 within the recess 16 in the neck-piece 11 is shortened. The connecting element, generally indicated by the numeral 24, for joining the head 10 with the body is so constructed, in the present embodiment, that it may be detachably connected to the head and neck-piece of the body to facilitate the mounting operation of said head and its removal in the event that it should be desired to replace or repair said head. As shown, the connecting member 24 comprises two strips 25 riveted or otherwise secured in abutting relation along the intermediate portions and provided at their lower ends with diverging resilient arms 26 substantially similar to the arms 21, the extremities 27 of said arms being bent outwardly so as to engage in the grooves 18 formed in the recess 16 of the neck-piece. Again, as in Figure 1, the head 12 has a turning movement upon the body which is limited by contact of the lower ends of the arms 26 with the abutment 23. In the operation of mounting the head in position, the connecting member 24 is first disposed upon the neck-piece 11 by pressing the resilient arms 26 together and inserting them into the recess 16 in the same manner as described in connection with the arms 21. This operation is accomplished with the head 12 detached from the connecting member 24 as distinguished from the embodiment of Figure 1 in which the connecting member is permanently joined to said head by affixing the yoke portion 19 of said connecting member to the rod 20.

In order that the head 12 is Figure 3 may be 40 detachably joined to the connecting member 24, the upper resilient ends of the strips 25 terminate in diverging fingers 28 which form an entrant slot for the rod 20 to guide the same into superposed recesses 29 both of which are in communication with said slot, said recesses being formed by bowing the strips 25 at opposed points. When positioning the head upon the body, the connecting member 24 is inserted into the opening in said head until the rod 20 is engaged between the fingers 28 whereupon continued movement of the head toward its position on the neck portion of the body 10 will cause said rod to spread apart the resilient fingers 28 until the rod 20 has passed the inner ends of said fingers and entered the uppermost recess 29. At this point, should the fit between the head 12 and body 10 be insufficiently snug, the head may then be forced further downwardly upon the body until the rod 20 enters the lower recess 29 of the connecting member, 60 whereupon a sufficiently close engagement between the head and body should be obtained. It will be apparent from this construction that the head 12 may be easily and quickly mounted in proper position upon the body 10 and removed 65 therefrom whenever desired without using tools to perform these operations. To properly center the connecting member 24 with respect to the attaching rod 20, the latter may be crimped at its center portion as indicated at 30 with the crimped 70 portions disposed on opposite sides of the bowed parts of the strips 25 which form the recesses 29.

The body 10, neck-piece 11 and head 12 of Figure 5 are identical in construction to the equivalent elements shown in Figure 1. The 75 connecting member 31 illustrated in Figure 5

comprises two strips 32, similar to the strips 25 of Figure 3 and having their intermediate portions secured together in abutting relation in a like manner. The resilient lower ends of the strips are diverged to form the arms 33 which are 5 engaged in the neck-piece in the same manner as described in connection with the arms 21. The upper ends of the strips 32 are bowed as indicated at 34 to form a recess for receiving the rod 20 and the extremities of said strips, from said bowed portions, diverge in a diagonal direction relative to the intermediate portions of said strips to form the fingers 35 which define an entrant slot communicating with the recess made by said bowed portions 34. With the fingers 35 thus inclined with respect to the remainder of the strips, it will be understood that when mounting the head 12 is position the same will have to be tilted to engage the rod 20 between said fingers, and it will be further understood that after the rod 20 10 is in position within the recess formed by the bowed portions 34 the latter will, due to their disposition relative to the rod 20, resist, to a greater extent than the bowed portions of the member 24 of Figure 3, a direct outward pull upon 15 the head 12 which would tend to dislodge said head from the body.

What is claimed is:

1. In a doll, a body, a head mounted thereon for turning movement, a neck-piece fitted into 30 said body and having an abutment, a retaining member connecting said head with said neck-piece and turnable with said head, said retaining member having means normally spaced from said abutment and engageable therewith, 35 only when said head is turned, to limit the turning movement.

2. In a doll, a body, a neck piece fitting in said body and having a recess therein provided with a lateral channel at its inner end, a head turnable on said body, a connecting member joining said head with said neck-piece and including resilient arms extending into said recess and engageable with a wall of said channel, and an abutment in said recess against which said arms 40 contact to limit the turning movement of said head.

3. In a doll, a body, a head turnable thereon, an abutment, means detachably connected to both the body and head for releasably joining 50 the same together, and means spaced from said abutment when the head is straight on said body and movable into engagement with said abutment when said head is turned to limit the turning movement.

4. In a doll, a body, a head turnable thereon, attaching elements in said body and head, and a connecting element having bifurcated portions at each end thereof releasably engageable with said attaching elements, one of said bifurcated 60 portions comprising divergent fingers having a recess at the inner ends thereof for receiving one of said attaching elements.

5. In a doll, a body, a head, an attaching member in said head, a neck-piece within said 65 body and having a recess therein, a connecting member provided at one end with resilient arms engageable in said recess to support said member in position on the neck-piece, and being further provided at its other end with divergent 70 contractile fingers and a recess at the inner ends thereof, said fingers constituting an entrant slot for guiding said attaching member into the latter recess and yieldably retaining the same there- 75 in.

6. In a doll, a body, a neck-piece fitting in said body and having a recess therein provided with grooves at its inner end, an attaching member in said head, a connecting member joining said head with said neck-piece and provided at one end with resilient arms insertable in the recess in said neck-piece and having extremities engageable in the grooves in said recess, said connecting member being further provided at 10 its other end with divergent contractile fingers and a recess at the inner ends thereof, said fingers constituting an entrant slot for guiding said attaching member into the latter recess and yieldably retaining the same therein, and an 15 abutment in the recess in said neck-piece against

which said resilient arms contact to limit the turning movement of said head relative to said body.

7. In a doll, a neck piece, a head mounted thereon for turning movement, said neck piece 5 being adapted to be releasably joined to a body, an abutment on one of said elements, retaining means connecting said neck piece and head, a part on said connecting means spaced from said abutment, said part and abutment being in the 10 same path of travel and engageable with each other, when the head is turned, to prevent the turning movement of the head beyond the plane of said parts when so engaged.

MARIE WITTMANN. 15
